UNITED STATES PATENT OFFICE.

MELCHIOR ZWICKY, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

SELVAGE-REENFORCING ATTACHMENT FOR FULL-FASHIONED KNITTING MACHINES.

1,417,290.

Specification of Letters Patent. Patented May 23, 1922.

Application filed January 20, 1920. Serial No. 352,798.

To all whom it may concern:

Be it known that I, MELCHIOR ZWICKY, a citizen of the United States, residing at Wyomissing, in the county of Berks and 5 State of Pennsylvania, have invented certain new and useful Improvements in Selvage-Reenforcing Attachments for Full-Fashioned Knitting Machines, of which the following is a specification.

10 This invention relates to full fashioned knitting machines, and particularly to means for forming a re-enforced selvage edge on the knitted fabric as hereinafter fully described in connection with the accompanying 15 drawing, the novel features being specifically pointed out in the claim.

Fig. 1 is a cross-sectional view through an end portion of a full fashioned knitting machine, showing a plating narrowing nut embodying my invention and its relation to certain coacting parts of the machine.

Fig. 2 is a corresponding enlarged view of the inner or plating carrier-rod stop nut, showing the specially provided stop member 25 in operative position, with the plating stop member indicated in retracted position.

Fig. 3 is a plan view corresponding with Fig. 2, the plating stop member being removed.

30 Fig. 4 is a cross-sectional view on the line 4—4 of Fig. 2, the plating stop member being indicated in its operative position.

The type of machine to which my invention applies is sufficiently indicated in Fig. 1, 35 and the stop nut arrangement to which it is particularly adapted is more fully set forth in Janssen-Zwicky Patent No. 1,079,915, issued November 25, 1913; the series of thread-carrier rods 10 extending through a passage- 40 way 11 in the stop nut 12 therefor as shown in the drawings, to the usual end stop nut which is not illustrated.

Both these stop nuts are carried by the controlling screw 13, which latter is operated as usual to automatically position them for the narrowing operation. The carrier rods are operated by the usual coulier movement through coulier lever 14 and rod connected friction boxes 15 on friction rod

16, the actual movements of the rods in one direction being limited by said end stop nut and in the other by said stop nut 12, the latter being termed the plating stop nut as it is particularly adapted for cooperation with carrier rods which are provided with 55 plating threads for well known plating operations.

These plating rods 10^a are provided with properly fixed stop dogs 20, which at determined times contact with a plating rod stop member 21; said member 21 being pivoted at 22, and its pivotal movements being automatically effected by a controller bar 23 so as to lower said stop member into the recess 31 between the rigid top bars 30 30 of the nut 60 extension for contact with said dogs 20 as indicated in Figs. 1 and 4; or so as to raise the same, as indicated in Fig. 2, to permit free passage of said dogs through the nut 65 passage-way 11.

When plating is employed merely to reenforce the stocking at heel and toe, as is commonly done, it is desirable that provision be made for reenforcing the selvage edges of the stocking beyond said plated portions. For 75 this purpose I provide selvage thread carrier rods 10^b, each having a specially located stop dog 40, and in connection therewith I provide said plating stop nut 12 with a separate selvage rod stop member 41 arranged 80 to swing thereon in a different plane from that of the plating rod stop member 21; said selvage rod stop member being pivoted at 42 against the outer face of a rigid top bar 30 of the nut, and having its free end 85 adapted to seat in a fixed lock 43 thereon when its dog engaging portion 44 depends into the rod passage way 11 so as to contact with the selvage rod dog 40. The other selvage rod 10^b is controlled at the opposite 90 end of the machine in a similar manner.

During the plating operation the plating stop member 21 is automatically operated as usual, with the selvage stop member 41 thrown out of action; and when the plating 95 operation is stopped as usual, the selvage rod is merely thrown into operation with the selvage stop member in acting position, the

fixed narrowing movement of the stop nut 12 serving alike for both the plating and selvage re-enforcing operations.

What I claim is:

- 5 In a full fashioned knitting machine having a carrier rod stop screw, thread carrier rods certain of which carry selvage threads and are provided with stop dogs, and others of which carry plating threads only and are

provided with differently located dogs, and 10 a plating nut on said screw carrying both a plating rod stop member and a separate selvage rod stop member, said members being arranged to swing independently into and out of dog-contacting position. 15

In testimony whereof I affix my signature.

MELCHIOR ZWICKY.
